UNITED STATES PATENT OFFICE.

ERNEST G. UNGER, OF NEW YORK, N. Y.

AUTOMATIC LOCKING CLAMP.

Application filed March 10, 1927. Serial No. 174,404.

The invention relates in general to a two-jaw clamp of general application, and herein disclosed to be of the type which comprises a pair of pivotally connected recessed 5 jaw plates automatically locked in a plurality of closed positions. The present disclosure constitutes an improvement over the device disclosed in my copending application on automatic locking clamps filed February 12, 1925, Serial No. 8,636 and like the invention disclosed in said copending application is particularly designed for clamping or crushing a thick paper tube into closed position incidental to practicing the art of 10 permanent waving of hair.

In the prior application, the locking feature was characterized by a lever pivoted to one of the two clamping jaws and which lever is provided with ratchet teeth for engaging a pin on the other jaw for securing the clamp in any one of its plurality of closed positions. In using devices of the types disclosed, it is necessary to exert a rather powerful action on the clamping jaws 15 to move the same into closed position against the resistance of the stiff paper tube and its contained coil of hair, and this resistance to closing movement of course increases rapidly as the jaws are moved closer and closer together. The tendency of the clamped tube to expand reacts on the locking elements and exerts a locking effect on the pin and ratchet connection. In order to overcome the tendency of the crushed tube to secure the fastening means in locked position, it is of course necessary to overcome the expanding force exerted by the clamped tube. This is 20 relatively easy where there is a long lever- 25 age effect between the pivotal mounting of the ratchet lever and the point of engagement with the pin on the other clamping jaw, but becomes extremely difficult as the pin on the other jaw is advanced into its succeeding positions closer and closer to the 30 pivotal mounting of the ratchet. Differently 35 expressed, it means that when the clamp is drawn up tight, it is extremely difficult to move it into a still tighter position. It is 40 required in this art that the paper tubes be crushed into practically air tight engagement 45 with the contained coil of hair so as to minimize the possibility of steam leakage on to the head of the person under treatment.

Accordingly, the primary object of the invention is to provide, in a device of the class outlined, a locking connection between the jaws designed to lock the same in a plurality of closed positions and in which it will be no more difficult to release the fastening means from one than from any other of the positions in which the clamp is tightly engaging the clamped body.

Broadly, this object is attained by reversing the pin and ratchet connection featured in the previously filed application so as to maintain the work arm of the locking lever, that is the arm connecting the jaws, a constant distance in all its operative positions securing the jaws in their closed relation. 70 Differently expressed, a single tooth on the lock controlling lever in its engagement with any one of the teeth on the other jaw is maintained spaced in fixed relation to its pivotal mounting.

While the invention has been specifically described in its application to crushing the usual paper tubes into engagement with a contained coil of hair, it is obviously within the scope of the disclosure to utilize the clamp to engage the hair coil directly and without the interposition of any form of covering. It is further possible to utilize the clamp as a shield to directly engage the hair strand adjacent the head.

Accordingly another object of the invention is to provide a scalp shield which can be readily mounted in position to prevent escape of steam from the hair on to the scalp and which can be quickly disengaged from the hair strand at the termination of the hair treatment.

Various other objects and advantages of the invention will be in part obvious from an inspection of the accompanying drawings 95 and in part will be more fully set forth in the following particular description of one form of mechanism embodying my invention, and the invention also consists in certain new and novel features of construction 100 and combination of parts hereinafter set forth and claimed.

In the accompanying drawing:

Fig. 1 is a transverse, sectional view taken through a coil of hair wrapped on a winder contained within a paper tube and having closed thereon a clamp constituting a preferred embodiment of my invention; and

Fig. 2 is a view of the clamp shown in Fig. 1 in open position and removed from the hair coil.

- In the drawings and referring first to Fig. 1, there is shown a strand of hair wound spirally on a rod or curler *b* and contained within a crushable paper tube *c*, all as is well known in the art of permanent hair waving. In the use of the clamp as shown in this figure, the inner end of the tube *c* adjacent the person's head is closed by a clamp constituting the subject matter of this disclosure. Where the clamp is used as a scalp shield, the jaws are closed directly on the hair strand and in this case the clamp is spaced from and independent of the rod *b* and tube *c* and is located intermediate the base of the strand of hair and the adjacent end of the curler rod *b*.
- 20 The clamp or shield comprises two coacting jaws 10 and 11, pivotally connected adjacent one end by means of a pivot pin 12. The jaws are somewhat U-shaped and are each provided on their inner edges with a U-recess edge 13. These recessed edges coact when the jaws are moved towards each other to crush the tube *c* into engagement with the contained hair coil and beyond the partially closed position shown in Fig. 1.
- 25 The jaw 10 is provided adjacent its free edge with an outstanding finger engaging ear 14. Adjacent the free end the plate forming the jaw 10 is perforated and punched to provide with a series of ratchet teeth 15 concentrically disposed relative to the pivot pin 12 and preferably formed by saw tooth corrugations struck out from the plate and bent out of the plane of the plate.
- 30 The coacting jaw member 11 is offset from the plane of the jaw 10 so that the free end 17 is movable in a plane parallel to and offset from the side of the jaw 10 opposite the side from which the teeth 15 project. In this way the free end 17 of the jaw 11 can move past the free end of the jaw 10 when moved into locked position as indicated in dotted lines in Fig. 1.
- 35 The jaw 11 has a bell-crank shaped pawl 18 pivoted thereto on a pivot pin 19 offset from the pin 12. The pawl 18 conforms somewhat in configuration to that of the jaw 11, extends parallel to the same and is disposed so as to lap the side of the jaw 10 from which projects the ratchet teeth 15.
- 40 The forwardly projecting or work arm of the pawl is provided on its inner side with a single tooth or detent 20. The tooth is designed to be fed across the line of ratchet teeth 15 and arranged so that one of the teeth will hold the detent 20 and thus secure the jaws in adjustable clamped position depending upon which one of the ratchet teeth are engaged by the detent. The outer edge of the pawl 18 is provided with an outstanding ear 22 positioned on the side of the pivot

19 opposite the side which is provided with the detent 20. Lugs 23 and 24 bent from the outer edge of the pawl on opposite sides of the finger engaging ear 22 overlap the adjacent outer edge of the jaw 11 and act to limit the swing of the pawl in both directions about its pivotal connection at 19.

From this connection, it will be understood that the operator's fingers engaging the outer side of the ears 14 and 22 can pinch the same towards each other with the thumb and finger of one hand and thus move the jaws toward their closing position as shown in Fig. 1. At the same time, such movement will swing the pawl into position to cause the detent 20 to ride over the line of ratchet teeth 15 into and beyond the position shown in Fig. 1 and thus successively engage each tooth. Pressure is continued as long as the strength of the operator is sufficient to overcome the resistance offered by the crushed tube *c* or other article clamped between the jaws.

It is noted during this closing movement that the operator bears on the ear 22 to swing the work arm indicated by the line *d*—*e* and that the length of this work arm is constant for all positions of the tooth 20, when in engagement with any of the ratchet teeth 15. The distance between the pivotal point 19 and the engaged tooth is not increased when the jaws become closer as is the case in the showing in the previously filed application. While it is, of course, true that the closer together the clamping jaws are moved, the greater is the jaw opening force of the paper tube *c* or other clamped article, this has no increase of leverage effect holding the detent to the engaged tooth. The operator retains the releasing leverage provided by the arm *d*—*e* and the resisting force of the crushed tube is not acting through a short leverage as is true in the preceding device.

As the closing movement of the jaws can be controlled by the two projecting finger pieces 14 and 22, it is possible to secure the clamp especially when used as a shield close to the scalp and the operator can reach with her fingers into a mass of hair and similar clamps and simply press together the projecting finger pieces. Similarly in loosening the clamp, the operator can push her finger or a pencil-like tool into the space between the fingers and this will unlatch the pawl. This ease of access to the locking element is vitally necessary in a situation where access is difficult.

The device disclosed features the omission of springs or other resilient devices which in the case of shields are frequently highly heated and thus lose their resiliency.

Having thus described my invention, I claim:

1. In a clamp, the combination of a pair

- of jaws pivotally connected, said clamp provided with two outstanding finger pieces and otherwise free of marginal projections, one of said outstanding fingerpieces projecting from one of said jaws, a pawl pivoted to the other jaw and provided with an outstanding finger piece constituting the other finger piece and adapted for swinging the pawl relative to both jaws, said pawl provided with a single tooth and the first named jaw provided with a curved rack disposed concentrically of the pivotal connection between the jaws, any tooth of said rack adapted to be engaged by the pawl tooth for securing the jaws in one of a plurality of closed positions depending on which tooth of the rack is engaged when the two finger pieces are pinched towards each other, the outer, opposite sides of said finger pieces constituting finger engaging faces adapted when the finger pieces are pinched together to act on the pawl to swing the same into engagement with the rack and acting through the pawl to move the associated jaw into closed relation to the other jaw.
2. In a clamp, the combination of a pair of jaws pivotally connected, one of said jaws provided with an outstanding finger-piece, a pawl pivoted to the other jaw and provided with an outstanding finger-piece constituting the means for swinging the pawl relative to both jaws, said pawl provided with a single tooth and the first named jaw provided with a rack, any tooth of said rack adapted to be engaged by the pawl tooth for securing the jaws in one of a plurality of closed positions depending on which tooth of the rack is engaged and the finger piece on the pawl having opposite sides exposed to permit the operator to engage selectively opposite sides of the finger piece to move the pawl in both directions.
3. In a clamp, the combination of a pair of jaws pivotally connected, a pawl pivoted to one of the jaws for a limited movement in a plane parallel to the plane of movement of the jaws and provided with a detent, the other jaw provided with a series of slits in spaced relation to its edges, the portions between the slits bent out of plane of the

jaw to form a rack adapted to be engaged by the detent for automatically securing the jaws in a plurality of closed positions.

4. In a device of the class described, the combination of a pair of pivotally connected jaws, means for fastening the jaws in any one of a plurality of closed positions, said fastening means including a manually actuated element pivoted adjacent its mid length to one of the jaws to swing freely and adapted to be swung into engagement with a co-acting element on the other jaw, the distance between the pivotal mounting of said manually actuated element and its point of engagement with the coacting element being of the same length for all of its operative jaw-fastening positions, and said manually actuated member provided with a finger piece projecting from the outer edge thereof, adjacent its pivotal connection with its associated jaw and intermediate its opposite ends.

5. A clamp comprising a pair of pivotally connected jaws, a pawl pivoted to one of the jaws for movement in a plane parallel to the plane of the jaws and provided with a finger engaging part projecting beyond the edge of the associated jaw for moving the pawl in both directions relative to both jaws, the other jaw provided with a series of teeth formed integral therewith, offset from the plane of said jaw and adapted to be engaged by the pawl to secure the jaws in a plurality of closed positions.

6. A clamp comprising a pair of pivotally connected jaws, a freely swinging pawl pivoted to one of the jaws and provided with a finger engaging part constituting the means for moving the pawl relative to both jaws to and from an engaging position, the other jaw provided with a series of teeth adapted to be engaged by the pawl to secure the jaws in a plurality of closed positions and said pawl provided with fixed stops for limiting its swinging movement in both directions into and out of engagement with the teeth.

Signed at New York city, in the county of New York and State of New York this 28th day of February, A. D. 1927.

ERNEST G. UNGER.
